MINING MACHINE

Morris P. Holmes, Claremont, N. H., assignor to
 Sullivan Machinery Company, a corporation of
 Massachusetts

Application July 14, 1930. Serial No. 467,790

41 Claims. (Cl. 262—28)

This invention relates to mining machines and more particularly to coal mining machines of the track cutting, shear cutter type.

An object of this invention is to provide an improved coal mining machine. Another object is to provide an improved track cutting shearing machine. A further object is to provide an improved mining machine of the track cutting, shear cutter type having improved means for operating the cutting mechanism. Yet another object is to provide an improved coal mining machine having improved cutting mechanism and improved means for guiding the cutting mechanism during the cutting operation. Still another object is to provide an improved cutting mechanism including a pivoted kerf cutter and improved means for swinging the kerf cutter about its pivot and for effecting rectilinear summing and withdrawal movements of said kerf cutter during the cutting operation. A still further object is to provide an improved mining machine having an improved general arrangement of parts and improved mechanisms for accomplishing the various functions of the machine. These and other objects and advantages of this invention will, however, hereinafter more fully appear in the course of the following description and as more particularly pointed out in the appended claims.

In the accompanying drawings there is shown for purposes of illustration one form which the invention may assume in practice.

In these drawings,—

Fig. 1 is a plan view of an illustrative embodiment of the improved mining machine;

Fig. 2 is a side elevational view of the machine shown in Fig. 1;

Fig. 3 is an enlarged horizontal sectional view taken substantially on line 3—3 of Fig. 2;

Fig. 4 is a longitudinally extending vertical sectional view taken substantially on line 4—4 of Fig. 3;

Fig. 5 is a transverse vertical sectional view taken substantially on line 5—5 of Fig. 2;

Fig. 6 is a detail view illustrating the feed sprocket and the cooperating guide sheaves; and

Fig. 7 is a detail sectional view illustrating the clamp for holding the cutting mechanism in position on the guiding frame.

In the illustrative embodiment of the invention there is shown a coal mining machine of the track cutting, shear cutter type generally comprising a truck 1 supported by wheels 2 adapted to travel along a mine trackway 3. Mounted on the truck 1 for horizontal swinging movement relative thereto about a vertical axis as at 4 is

an elongated guideway or track 5 on which is supported for movement therealong the improved kerf cutting mechanism generally designated 6. Improved truck propulsion means generally designated 7 is provided for propelling the machine along the mine trackway during transport.

Now referring to the improved wheeled truck and the improved guiding frame or track for the cutting mechanism it will be observed that the truck 1 is of a fabricated construction comprising parallel longitudinally extending side members 8 herein in the form of angle irons held in rigid spaced relationship by means of transverse trusses in a usual manner. Mounted on the truck 1 substantially midway between its ends and sides is an annular frame or swivel bearing 9. Supported by the angle irons 8 and the upturned flanges of the swivel bearing 9 is a series of rollers 10 supporting a horizontal swivel plate 11 which turns about the axis 4. Secured to this swivel plate is an annular bearing 12 rotatably mounted on a bearing sleeve 13 supported by an upstanding cylindrical hub 14 herein formed integral with the frame of the swivel bearing. It will thus be seen that these elements form a horizontal turntable 75 mounting for the guiding frame or track 5. The improved guiding frame structure includes parallel longitudinally extending guide members 15, herein in the form of channel irons, and extending longitudinally of the truck a substantial distance in advance of the front end thereof and overlying the truck as clearly shown in Figs. 1 and 2. Running along the channel irons as a trackway are rollers 16 supported by stub shafts 17 secured to the depending flanges of a plurality of angle members 18 herein arranged parallel with the channel irons 15 and secured to the bottom plate 19 of the supporting frame 20 of the cutting mechanism 6. It will thus be seen that these elements cooperate 80 to form what might be termed a rolling supporting structure movable along the guiding frame 5 and supporting the cutting mechanism. The longitudinally extending channel irons of the guiding frame 5 are braced by a transverse connecting frame 21 which together with the plate 11 maintains the channel irons 15 in rigid lateral spaced relation. The transverse frame 21 is bowed 85 downwardly so as not to interfere with the cutting mechanism when the kerf cutter is in its lower rearward position. For supporting the forward end of the guiding frame during operation of the cutting mechanism there are provided at opposite sides of the outer channel irons 15 swivel brackets 100 each having pivotally connected thereto ad-

105

justable screw jacks 23 and 24. These jacks when positioned between the mine roof and mine floor form an adjustable support for the forward end of the guiding frame 5. During transport of the machine about the mine these jacks may either be disconnected from the swivel brackets or swung out of the way in any suitable manner.

Now referring to the improved cutting mechanism and more particularly to the improved driving means therefor, it will be observed that carried by the supporting frame 20 of the cutting mechanism is a motor 25 herein preferably of the reversible electric type having its armature shaft horizontally disposed and extending longitudinally of the guiding frame 5. This motor is arranged at the rear side of the supporting frame 20 and at one side of the longitudinal vertical center of the guiding frame, as shown in Fig. 1. Secured to the forward end of the motor armature shaft, as shown in Fig. 3, is a bevel pinion 26 meshing with a bevel gear 27 keyed to a horizontal shaft 28 extending transversely of and suitably journaled within the supporting frame 20. Herein formed integral with the shaft 28 is a spur pinion 29 meshing with a large spur gear 30 connectible with, and which herein constitutes the main driving gear for, a cutter chain drive sprocket 31. This sprocket engages and drives an endless cutter bit carrying cutter chain 32 guided for orbital movement about the margin of an elongated plane cutter bar 33. This cutter bar is arranged edgewise to swing in a vertical plane midway between the sides of the guiding frame and is supported for swinging movement by a bearing bracket 34 attached to the cutter bar and rotatably mounted at 35 on a bearing support member 36. Also for guiding the cutter bar during its swinging movement there is provided a circular flange 37 with which a grooved guide and abutment member 38, attached to the cutter bar, cooperates. This circular flange 37 as shown in Fig. 2 is provided with end abutments 39 with which the member 38 is engageable to limit the up and down swinging movements of the cutter bar. Again referring to the driving means for the cutting mechanism it will be noted that the spur gear 30 is provided with a hub 40 keyed to a horizontal shaft 41 arranged parallel with the shaft 28 in advance thereof and likewise suitably journaled within the supporting frame 20. Surrounding this hub 40 and supported thereby is a bearing sleeve 42 on which the cutter chain sprocket 31 is journaled, a suitable retaining ring 43 suitably attached to the hub 40 holding the bearing and sprocket in position on the hub. The spur gear 30 is connectible with the cutter chain sprocket 31 by means of a pin clutch 44 comprising slidable clutch pins 45 guided in apertures 46 formed in the gear 30. These clutch pins cooperate with sockets or jaws 47 formed in the hub of the cutter chain sprocket and are movable into and out of their clutched position by means of a shipper member 48. The shipper member is slidably mounted on a bearing sleeve carried by a cylindrical support 49 of a detachable bearing plate 50 secured to the supporting frame 20. This shifting member 48 for the clutch pins has secured thereto an annular grooved member 51 with which a shipper yoke 52 cooperates, this shipper yoke being fixed to a vertical shaft having an operating handle 53 conveniently arranged at the top of the supporting frame 20.

In specifically describing the improved mechanism for swinging the cutter bar 33 about its pivot, it will be noted that the gear 30 consti-

tutes a driving element for the transverse shaft 41, and connected to this shaft by a semi-permanent clutch 54 is an alined shaft 55 likewise suitably journaled within the supporting frame 20. Fixed to this shaft for rotation therewith is a worm 56 meshing with a worm wheel 57 suitably journaled on a longitudinally extending horizontal shaft 58. This shaft is suitably journaled within the supporting frame 20, and the worm wheel 57 is connectible with this shaft to effect driving of the latter by means of a multiple disc clutch 59. Secured to the forward end of and driven by the shaft 58 is a worm 60 meshing with a worm wheel 61 keyed to a transverse shaft 62 suitably journaled within the supporting frame 20. This shaft 62 is arranged parallel with and in advance of the alined shafts 41, 55 and has herein formed integral therewith a spur pinion 63 meshing with the teeth of an arcuate rack or gear segment 64 attached to the cutter bar 33. It will therefore be evident that when the clutch 59 is applied the cutter bar may be swung about its pivot in one direction at a relatively high bar-positioning speed through the worm gears 56, 57, shaft 58, worm gears 60, 61 and spur pinion 63 meshing with the gear segment 64 attached to the cutter bar 33.

To effect swinging movement of the cutter bar in either of opposite directions at a relatively slow speed appropriate for cutting there is provided a bevel gear 65 (see Fig. 5) keyed to the shaft 55 and meshing with a bevel gear 66 secured to a vertical shaft suitably journaled within the supporting frame 20. This bevel gear 66 meshes with a reverse bevel 67 loosely journaled on a sleeve 68 in turn loosely journaled on the shaft 55. Splined to this sleeve is a jaw clutch member 69 having clutch teeth connectible with clutch teeth carried by the reverse bevels 65, 67. This clutch member is provided with a suitable shipper yoke 70 having an operating lever 71. Keyed to the outer end of the sleeve 68 is a spur gear 72 meshing as shown in Fig. 3 with a spur gear 73 keyed to a horizontal shaft 74 arranged parallel with and in advance of the shaft 55 and likewise suitably journaled in the supporting frame 20. Herein, formed integral with this shaft, is a worm 75 meshing with a worm wheel 76 coaxial with the worm wheel 57 and suitably journaled on the shaft 58. This worm wheel is connectible with the shaft 58 by a multiple disc clutch 77. The operating means for the friction clutches 59, 77 includes a clutch member 78 interposed between the worm wheels 76 and 57 and slidably mounted on the shaft 58. This clutch actuating member is provided with suitable shipper mechanism including a shipper yoke 79 secured to a vertical shaft having an operating handle 80 arranged at the top of the supporting frame 20 in adjacency with the handle 53 referred to above. It will thus be seen that upon an application of the clutch 77 (it being understood that the clutch 59 is released), and when one or the other of the reverse bevels 65, 67 is connected with the sleeve 68 the cutter bar may be swung about its pivot in either of opposite directions at a relatively slow cutting speed through spur gears 72, 73, shaft 74, worm gears 75, 76, shaft 58, worm gears 60, 61 and the spur pinion 63 meshing with the gear segment 64 attached to the cutter bar 33. The worm gears 60 and 61 are self-locking and automatically maintain, when the clutches 59, 77 are released, the cutter bar in its different angular positions about its pivotal axis.

Now referring to the mechanism for moving the cutting mechanism along the guiding frame or track 5 it will be observed that journaled on a bearing sleeve supported by the shaft 58 is a feed 5 operating member 85 herein in the form of a chain driving sprocket engaging a flexible feeding element 86 herein in the form of a loose link feed chain. This feed chain is guided relative to the feed sprocket 85 by means of guide sprockets or 10 sheaves 87 arranged on parallel axes at opposite sides of a vertical plane including the chain sprocket axis, and this feed chain passes around these guide sprockets and is connected at its forward end at 88 to one side of the forward end 15 of the guiding frame and at its rear end at 89 to one side of the rearward end of the guiding frame, this feed chain lying along the top of the guiding frame as shown in Figs. 1 and 2. In the present construction the chain sprocket 85 may 20 be driven in either of opposite directions at a relatively slow speed through the reverse mechanism 65, 67 and the worm gears 75, 76 and the chain sprocket 85 is connectible with the worm wheel 76 by a sliding jaw clutch 90 keyed to the hub of the chain sprocket and having clutch teeth connectible with the teeth of a clutch member 91 keyed to the hub of the worm wheel 76. Suitable shifting mechanism is provided for the 25 jaw clutch 90 including shipper yoke 92 secured to a transverse shaft having a suitable operating lever 93. It will thus be seen that the cutting mechanism may be fed either forwardly or rearwardly along the guiding frame 5 under the control of the jaw clutch 90 and that the feed may 30 be disconnected from the motor at will simply by releasing this jaw clutch. For holding the cutting mechanism in its different positions along the guideway 5 there is provided a clamp member 94 having serrations on its inner surface engageable with the outer surface of the adjacent channel iron 15 and operated by a set screw 35 threadedly engaged with a bracket 95 secured to the flange of the angle member 18 as shown in Fig. 7. This set screw has a pivoted operating handle 96 and is connected to the clamp member 94. When the set screw is tightened the clamp grips the channel iron thereby locking the cutting mechanism in position on the guiding frame 5.

30 The truck propulsion mechanism 7 herein includes a final driving element on the cutter supporting frame 20 which is engageable with an initial truck driving element on the truck when the cutting mechanism is in a predetermined position, i. e. its rearmost position, on the guiding frame. In specifically describing this truck propulsion mechanism it will be noted that keyed 35 to the shaft 41, as shown in Figs. 3 and 5, is a bevel gear 97 meshing with a bevel gear 98 keyed to a vertical shaft 99 arranged at one side of and suitably journaled within the supporting frame 20. Keyed to the lower end of this shaft is a spur gear 100 meshing with an intermediate or idler gear 101 suitably rotatably supported 40 by the frame 20 and meshing with and driving a spur gear 102. This spur gear 102, when the cutting mechanism is in its extreme rearward position on the guiding frame, overlies and is connectible, by means of a coaxial spur gear 102' and a clutch 103', with a spur gear 103 keyed to a vertical shaft 104 as shown in Fig. 5. Suitable operating means for the clutch 103' is provided and includes a shipper yoke 104', operating rod 105' and an operating handle 106' arranged at the rear end of the guiding frame. The 45 shaft 104 is arranged in the central longitudinal vertical center of the guiding frame and is suitably journaled within a bracket 105 secured to the swivel bearing 14. Herein formed integral with the shaft 104 is a bevel gear 106 meshing with reverse bevels 107 and 108 loosely journaled on a horizontal shaft 109 arranged transversely of the truck and suitably journaled within a gear housing 110 herein formed integral with the swivel bearing 14. Keyed to the opposite ends of this shaft are chain sprockets 111 and 112, the former connected through an endless chain 113 to a chain sprocket 114 secured to the front truck axle, while the latter is connected by an endless chain 115 engaging a chain sprocket 116 secured to the rear truck axle. It will further be evident that due to the arrangement of the gear 103, shaft 104, and bevel gear 106 with their axes coincident with the axis of swiveling movement of the guiding frame 5, the truck wheels may be driven irrespective of the angular position of the guiding frame relative to the truck thereby eliminating the necessity of having the guiding frame in an exact longitudinally alined position during transport of the 50 machine about the mine. The reverse bevels 107 and 108 are selectively connectible to the shaft 109 by multiple disc clutches 117 and 118 respectively, having suitable actuating mechanism including a shiftable clutch applying member 119 and a cooperating shipper yoke 120. It will thus be seen that when the cutting mechanism is in its rearmost position on the guiding frame 5 with the final driving gear 102' on the supporting frame 20 clutched to the initial driving gear 103 on the truck, the truck wheels may be driven in either of opposite directions at a relatively high transport speed by the shaft 41, bevel gears 94, 95, the spur gear train 100, 101, 102, 102', 103, one or the other of the reverse bevels 107, 108 and sprocket connections 111, 112, 113, 114, 115, and 116.

55 A frictional braking device 121 secured to the rear truck wheel axle is employed for controlling movement of the machine along a steeply inclined trackway and for holding the truck stationary during the cutting operation. This braking device is provided with suitable operating means including a brake lever 122 as shown in Fig. 2. Electrical energy is supplied to the driving motor 25 through a usual flexible conductor cable 123 wound upon a usual cable reel 124 suitably rotatably mounted on the rear end of the cutter supporting frame 20, and this cable reel is connected through usual flexible conductor 60 elements to the usual electrical controlling apparatus for the motor 25. For driving this cable reel to wind in or pay out the conductor cable 123 as the machine moves along the mine trackway there is provided as shown in Fig. 3, a spur gear 125 meshing with the spur pinion 29 above referred to. This spur gear 125 is keyed to a transverse shaft 126 suitably journaled within the supporting frame 20 and having rotatable therewith a pulley 127 connected by endless belt 128 to a pulley 129 secured to the cable reel 124. Engaging the driving belt 128 is an adjustable idler pulley 130 which when in its belt tightening position causes the cable reel to be driven by the pulley 127. When this pulley 130 is swung 65 upwardly the driving belt 128 is loosened permitting the belt to slip and thereby interrupting the drive between the pulleys 127 and 129. The means for adjusting the pulley 130 includes a link 131 connected to a crank 132 secured to 70

- a transverse operating rod having a usual adjusting lever 133. By swinging the lever 133 it will be evident that the idler pulley 130 may be raised and lowered at will.
- 5 The general mode of operation of the improved mining machine will now be briefly described. The machine is propelled about the mine by the motor 25 through the gear train 26, 27, 29, 30, 97, 98, 100, 101, 102 and 103 at a relatively high speed and in either of opposite directions under the control of the reversing mechanism 107, 108, 119. During transport of the machine about the mine the guiding frame and cutting mechanism are disposed in the position shown in Figs. 1 10 and 2 with the cutting mechanism held in its rearmost position and the final gear 102' of the cutting mechanism clutched to the initial gear 103 on the truck. As previously mentioned the jacks 23, 24 are either detached from the mining frame or swung up out of the way in any suitable manner. When the working face is reached and it is desired to insert a vertical or shear cut in the coal face directly in advance of the machine, the jacks 23, 24 are set up between the mine roof and mine floor thereby rigidly supporting the forward end of the guiding frame in the manner shown in Fig. 2. The clutch 69 is then shifted into a position to connect the bevel gear 65 to the sleeve 68 and upon connection of the clutch 90 the cutting mechanism is fed a slight distance forwardly relative to the guiding frame, the clutch 103' having of course disconnected gears 102, 103, the clutches 69, 90 thereafter being released. The friction clutch 77 20 is then applied and the cutter bar 33 is swung upwardly by power through the train of mechanism including pinion 63 meshing with the gear segment 64 attached to the cutter bar at a relatively high bar positioning speed. When the outer extremity of the cutter bar attains a position adjacent the mine roof, the clutch 77 is released and the self-locking worm gears 60, 61 automatically hold the cutter bar in this position. The clutch 69 is then adjusted to connect the proper bevel gear 65, 68 in driving relation with the sleeve 69 and upon connection of the clutch 90 the feed sprocket 85 is rotated in a direction to effect forward rectilinear feeding movement of the cutting mechanism relative to the guideway at a relatively slow cutting speed to effect sumping of the cutter bar within the coal, the clutches 69 and 90 thereafter being disconnected. The friction clutch 69 is then shifted to connect the bevel gear 67 to the sleeve 68 and upon application of the friction clutch 77 the cutter bar 33 is swung downwardly in its plane to effect a vertical swinging cut in the coal. After the completion of the swinging cut the clutch 77 is released and upon connection of the clutch 90 30 the cutting mechanism is fed rearwardly rectilinearly relative to the guiding frame at a slow cutting speed to effect the withdrawal movement of the cutter bar. The parts are then returned to their transport position as shown in Fig. 2 and the machine is bodily propelled along the mine trackway to another working place. If it is desired to cut a kerf at an angle relative to the central longitudinal vertical plane of the machine this may be accomplished simply by swinging the guiding frame 5 laterally about its axis of swiveling movement. The jacks 23, 24 are then adjusted and the cutter bar sumped in, swung downwardly in its plane and withdrawn from the coal in the manner described above.
- 35 It will also be noted that the guiding frame may

be swiveled into various angle positions relative to the truck and that under certain conditions kerfs may be cut in the coal at a substantial right angle to the longitudinal meridian line of the machine. The motor 25 is operative to effect 80 drive of the truck wheels irrespective of the angular position of the guiding frame about its swivel relative to the truck, thereby facilitating movement of the machine into its different cutting positions and at certain times permitting 85 movement of the machine when the guiding frame is disposed at a substantially right angle to the longitudinal dimension of the machine. As previously mentioned the brake 121 is used 90 to hold the machine during cutting operation and to control the movement of the machine along a steeply inclined trackway. These and various other advantages and modes of use of the improved mining machine will be clearly apparent to those skilled in the art.

95 As a result of this invention it will be noted that an improved coal mining machine of the track cutting shear cutter type is provided having improved means for driving and adjusting the cutting mechanism and for guiding the cutting mechanism during the cutting operation. It will further be noted that by the provision of the improved guiding frame structure it is possible to cut kerfs in coal when the machine is supported on a curved track, this being an especially desirable feature when cutting room necks. It will further be evident that by the provision of a stationary guiding frame mounted on the truck and along which the cutting mechanism moves and is guided during cutting operation, it is 100 possible to effect the cutting operation while supported on an uneven trackway, the cutting mechanism being wholly independent of the mine trackway for its guiding function during 105 the cutting operation.

110 While there is in this application specifically described one form which this invention may assume in practice, it will be understood that this form of the same is shown for purposes of illustration and that the invention may be modified 115 and embodied in various other forms without departing from its spirit or the scope of the appended claims.

115 What I claim as new and desire to secure by Letters Patent is:

- 120 1. In a mining machine, a portable support, an elongated guiding frame pivotally mounted thereon for horizontal movement relative thereto, kerf cutting mechanism mounted on said guiding frame for movement therealong and having a driving motor, and devices driven by said motor and operative irrespective of the angular position of said guiding frame about its pivotal axis for bodily propelling the machine.
- 125 2. In a mining machine, a portable support, an elongated guiding frame pivotally mounted thereon for horizontal swinging movement relative thereto, kerf cutting mechanism mounted on said guiding frame for movement therealong, a motor on said guiding frame, devices driven by said motor for actuating said cutting mechanism, and devices driven by said motor operative irrespective of the angular position of said guiding frame about its pivotal axis for bodily propelling the machine.
- 130 135 3. In a mining machine, a portable support, an elongated guiding frame pivotally mounted thereon for horizontal swinging movement relative thereto, kerf cutting mechanism mounted on said guiding frame for movement therealong, devices driven by said motor for actuating said cutting mechanism, and devices driven by said motor operative irrespective of the angular position of said guiding frame about its pivotal axis for bodily propelling the machine.
- 140 145 4. In a mining machine, a portable support, an elongated guiding frame pivotally mounted thereon for horizontal swinging movement relative thereto, kerf cutting mechanism mounted on said guiding frame for movement therealong, devices driven by said motor for actuating said cutting mechanism, and devices driven by said motor operative irrespective of the angular position of said guiding frame about its pivotal axis for bodily propelling the machine.
- 150

- a motor on said guiding frame, devices driven by said motor for driving said cutting mechanism, devices driven by said motor for moving said cutting mechanism along said guiding frame, 5 and devices driven by said motor and operative irrespective of the angular position of said guiding frame about its pivotal axis for bodily propelling the machine.
4. In a mining machine, a wheeled truck adapted to travel along a trackway, an elongated guiding frame pivotally mounted on said truck for swinging movement relative thereto, kerf cutting mechanism mounted on said guiding frame for movement therealong and including a motor, and devices driven by said motor for driving the truck wheels irrespective of the position of said guiding frame about its pivotal axis relative to said truck.
5. In a mining machine, a wheeled truck adapted to travel along a trackway, an elongated guiding frame pivotally mounted on said truck for horizontal swinging movement relative thereto, kerf cutting mechanism mounted on said guiding frame for movement therealong and including a motor, and devices driven by said motor and operative irrespective of the position of said guiding frame about its pivotal axis for driving the truck wheels to propel the machine.
6. In a mining machine, a wheeled truck adapted to travel along a trackway, an elongated guiding frame pivotally mounted on said truck for horizontal swinging movement relative thereto, kerf cutting mechanism mounted on said guiding frame for movement therealong and including a motor, devices driven by said motor for actuating said cutting mechanism, devices driven by said motor for moving said cutting mechanism along said guiding frame, and devices driven by said motor and operative irrespective of the position of said guiding frame about its pivotal axis relative to said truck for driving the truck wheels to propel the machine.
7. In a mining machine, a portable support, an elongated guiding frame pivotally mounted on said support for horizontal swinging movement relative thereto, kerf cutting mechanism mounted on said guiding frame for movement therealong, and motor operated devices for moving said cutting mechanism relative to said guiding frame including a feed operating member rotatable on an axis extending longitudinally of said guiding frame, and a cooperating flexible feeding element engaging said feed operating member and connected to the opposite ends of said guiding frame.
8. In a mining machine, a portable support, a guiding frame pivotally mounted on said support for horizontal swinging movement relative thereto, kerf cutting mechanism mounted on said guiding frame for movement therealong, and motor operated devices for moving said cutting mechanism relative to said guiding frame including a feed operating member rotatable on an axis extending longitudinally of said guiding frame, a cooperating flexible feeding element engaging said feed operating member and connected to the opposite ends of said guiding frame, and motor operated devices for rotating said feed operating member in either of opposite directions at a relatively slow cutting speed.
9. In a mining machine, a wheeled truck adapted to travel along a trackway, an elongated guiding frame pivotally mounted on said truck for horizontal swinging movement relative thereto, kerf cutting mechanism mounted on said guiding frame for movement therealong and including a frame, a kerf cutter pivotally mounted
- guiding frame for movement therealong including a motor, and devices driven by said motor and including a reversing mechanism carried by said truck between the truck wheel axes for driving the truck wheels in either of opposite directions.
10. In a mining machine, a wheeled truck adapted to travel along a trackway, a guiding frame pivotally mounted on said truck for horizontal swinging movement relative thereto, kerf cutting mechanism mounted on said guiding frame for movement therealong including a motor, and devices driven by said motor and including a reversing mechanism carried by said truck beneath the latter for driving the truck wheels in either of opposite directions while said motor runs continuously in the same direction.
11. In a mining machine, a guiding frame and devices for supporting said guiding frame including a swivel bracket on said guiding frame and separate oppositely acting jacks pivotally mounted on said bracket for independent swinging movement relative thereto.
12. In a mining machine, a guiding frame and devices for supporting said guiding frame including swivel brackets carried at the opposite sides of said guiding frame, each of said brackets having a plurality of screw jacks pivotally connected thereto for independent swinging movement relative thereto.
13. In a mining machine, a wheeled truck adapted to travel along a trackway, a guiding frame pivotally mounted on said truck for horizontal swinging movement relative thereto, kerf cutting mechanism mounted on said guiding frame for movement therealong, and devices including a power actuated element on said kerf cutting mechanism and operative when said kerf cutting mechanism is in a predetermined position on said guiding frame for driving the truck wheels irrespective of the angular position of said guiding frame relative to said truck.
14. In a mining machine, a wheeled truck adapted to travel along a trackway, a guiding frame pivotally mounted on said truck for horizontal swinging movement relative thereto, kerf cutting mechanism mounted on said guiding frame for movement therealong and including a pivoted kerf cutter and a driving motor therefor, and devices driven by said motor and operative when said kerf cutting mechanism is in a predetermined position on said guiding frame for driving the truck wheels irrespective of the angular position of said guiding frame relative to said truck.
15. In a mining machine, a wheeled truck adapted to travel along a trackway, a guiding frame pivotally mounted on said truck for horizontal swinging movement relative thereto, kerf cutting mechanism mounted on said guiding frame and including a pivoted kerf cutter and a driving motor therefor, devices driven by said motor for moving said cutting mechanism relative to said guiding frame, and devices driven by said motor and operative when said cutting mechanism is in a predetermined position on said guiding frame for driving the truck wheels irrespective of the angular position of said guiding frame relative to said truck.
16. In a mining machine, a portable support, a guiding frame pivotally mounted on said support for horizontal swinging movement relative thereto, kerf cutting mechanism mounted on said guiding frame for movement therealong and including a frame, a kerf cutter pivotally mounted

- on said frame and a driving motor on said frame for actuating said kerf cutter, and devices for supplying electrical energy to said motor including power supply and control devices carried by said kerf cutter supporting frame, said power supply devices including a power conductor winding reel mounted on said said kerf cutter supporting frame and movable therewith during the cutting operation.
17. In a mining machine, a portable support, an elongated guiding frame pivotally mounted thereon for horizontal swinging movement relative thereto, kerf cutting mechanism mounted on said guiding frame for movement therealong and having a driving motor, and devices driven by said motor and operative irrespectively of the angular position of said guiding frame about its pivotal axis for bodily propelling the entire machine and including releasable devices having an element movable along the axis of pivotal movement of said guiding frame.
18. In a mining machine, a wheeled truck adapted to travel along a trackway, an elongated guiding frame pivotally mounted on said truck for horizontal swinging movement relative thereto, kerf cutting mechanism mounted on said guiding frame for movement therealong, and devices including a power actuated element on said kerf cutting mechanism, a cooperating element on said truck, said elements being operative when said kerf cutting mechanism is in a predetermined position on said guiding frame and said elements are connected in driving relation for driving the truck wheels irrespective of the angular position of the guiding frame relative to the truck.
19. In a mining machine, a frame, a kerf cutter mounted thereon and including a cutter chain driving sprocket, a motor on said frame, driving connections between said motor and said kerf cutter including a kerf cutter driving element coaxial with said sprocket, a horizontal shaft driven thereby, and mechanism for bodily feeding the machine during the cutting operation including a parallel shaft, gearing connecting said shafts, a worm driven by said parallel shaft, and a worm wheel meshing with said worm.
20. In a mining machine, a frame, a kerf cutter mounted thereon and including a cutter chain driving sprocket, a motor on said frame, driving connections between said motor and said kerf cutter including a kerf cutter driving element coaxial with said sprocket, a horizontal shaft driven thereby, and mechanism for bodily feeding the machine during the cutting operation including a parallel shaft, gearing connecting said shafts, a worm driven by said parallel shaft, a worm wheel meshing with said worm, a feed member coaxial with and driven by said worm wheel.
21. In a mining machine, a frame, a kerf cutter pivotally mounted thereon, a motor on said frame, driving connections between said motor and said kerf cutter including a kerf cutter driving element aligned with the kerf cutter pivot, a shaft driven thereby, reversing mechanism coaxial with said shaft, and mechanism driven through said reversing mechanism for bodily feeding the machine in opposite directions during the cutting operation.
22. In a mining machine, a frame, a kerf cutter pivotally mounted thereon, a motor on said frame, driving connections between said motor and said kerf cutter including a kerf cutter driving element, a shaft driven thereby, and mechanism for swinging said kerf cutter relative to said frame at different speeds in opposite directions includ-
- ing plural speed gearing driven by said shaft and a shaft driven through said gearing and disposed on an axis extending longitudinally of said frame.
23. In a mining machine, a frame, a kerf cutter pivotally mounted thereon and including a cutter chain driving sprocket, a motor on said frame, driving connections between said motor and said kerf cutter including a kerf cutter driving element, a shaft driven by said driving element and coaxial with said sprocket, mechanism driven from one end of said shaft for swinging said kerf cutter, mechanism driven from the same end of said shaft for feeding the machine at a cutting speed, and mechanism driven from the opposite end of said shaft for propelling the machine at a high transport speed.
24. In a mining machine, a frame, a kerf cutter mounted on said frame for vertical swinging movement relative thereto, a motor on said frame, driving connections between said motor and said kerf cutter including a kerf cutter driving element, a horizontal transversely extending shaft driven by said driving element, mechanism driven from one end of said shaft for swinging said kerf cutter, mechanism driven from the same end of said shaft for feeding the machine at a cutting speed, and mechanism driven from the opposite end of said shaft for propelling the machine at a high transport speed.
25. In a mining machine, a supporting frame, a frame mounted thereon for horizontal swinging movement relative thereto, kerf cutting mechanism carried by said second frame, and mechanism carried by said second frame for propelling the machine including driving elements arranged with their axes alined with the axis of pivotal movement of said second frame, and a clutch element movable along the pivot axis of said second frame for connecting said elements in driving relation.
26. In a mining machine, a supporting frame, a frame mounted thereon for horizontal swinging movement relative thereto, kerf cutting mechanism carried by said second frame, mechanism carried by said second frame for propelling the machine including driving elements arranged with their axes alined with the axis of pivotal movement of said second frame, and mechanism for bodily feeding the kerf cutting mechanism relative to said second frame.
27. In a mining machine, a frame, kerf cutting mechanism carried thereby, a motor carried by said frame, mechanism driven by said motor for swinging said kerf cutting mechanism and for feeding the cutting mechanism in opposite directions at a cutting speed including a reversing gear mechanism, and mechanism driven by said motor for propelling the machine in opposite directions at a high transport speed including a reversing gear mechanism separate from said first mentioned reversing mechanism.
28. In a mining machine, a frame, a kerf cutter pivotally mounted on said frame, a motor on said frame, driving connections between said motor and said kerf cutter including a kerf cutter driving element coaxial with the kerf cutter pivot, a shaft driven by said driving element, mechanism driven by said shaft for feeding the kerf cutter during the cutting operation, and mechanism driven by said shaft for bodily propelling the machine during transport.
29. In a mining machine, a frame, a kerf cutter pivotally mounted on said frame, a motor on said frame, driving connections between said motor and said kerf cutter including a kerf cutter

- driving element coaxial with the kerf cutter pivot, a shaft driven by said kerf cutter driving element, mechanism driven from one end of said shaft for feeding the kerf cutter during the cutting operation, and mechanism driven from the opposite end of said shaft for bodily propelling the machine during transport. 30. In a mining machine, a frame, a kerf cutter pivotally mounted on said frame, a motor on said frame, driving connections between said motor and said kerf cutter including a kerf cutter driving element coaxial with the kerf cutter pivot, a horizontal shaft driven by said kerf cutter driving element, mechanism driven by said shaft for feeding the kerf cutter during the cutting operation, and mechanism driven by said horizontal shaft for bodily propelling the machine during transport. 31. In a mining machine, a frame, a kerf cutter pivotally mounted on said frame, a motor on said frame, driving connections between said motor and said kerf cutter including a kerf cutter driving element coaxial with the kerf cutter pivot, a horizontal transversely extending shaft driven by said kerf cutter driving element, mechanism driven by said shaft for feeding the kerf cutter during the cutting operation, and mechanism driven by said shaft for bodily propelling the machine during transport. 32. In a mining machine, a frame, a kerf cutter pivotally mounted on said frame, a motor on said frame, driving connections between said motor and said kerf cutter including a kerf cutter driving element coaxial with the kerf cutter pivot, a horizontal shaft driven by said kerf cutter driving element, mechanism driven from one end of said shaft for feeding the kerf cutter during the cutting operation, and mechanism driven from the opposite end of said horizontal shaft for bodily propelling the machine during transport. 33. In a mining machine, a frame, a kerf cutter pivotally mounted on said frame, a motor on said frame, driving connections between said motor and said kerf cutter including a kerf cutter driving element coaxial with the kerf cutter pivot, a horizontal transversely extending shaft driven by said kerf cutter driving element, mechanism driven from one end of said shaft for feeding the kerf cutter during the cutting operation, and mechanism driven from the opposite end of said shaft for bodily propelling the machine during transport. 34. In a mining machine, a frame, a kerf cutter pivotally mounted on said frame, a motor on said frame, driving connections between said motor and said kerf cutter including a kerf cutter driving element, a shaft driven by said driving element, mechanism driven by said shaft for swinging said kerf cutter, mechanism driven by said shaft for feeding the machine, and mechanism driven by said shaft for propelling the machine during transport. 35. In a mining machine, a frame, a kerf cutter pivotally mounted on said frame, a motor on said frame, driving connections between said motor and said kerf cutter including a kerf cutter driving element, a shaft driven by said driving element, mechanism driven from one end of said shaft for swinging said kerf cutter, mechanism driven by said shaft for feeding the machine, and mechanism driven by said shaft for propelling the machine during transport. 36. In a mining machine, a frame, a kerf cutter pivotally mounted on said frame, a motor on said frame, driving connections between said motor and said kerf cutter including a kerf cutter driving element, a horizontal shaft driven by said driving element, mechanism driven by said shaft for swinging said kerf cutter, mechanism driven by said shaft for feeding the machine, and mechanism driven by said shaft for propelling the machine during transport. 37. In a mining machine, a frame, a kerf cutter pivotally mounted on said frame, a motor on said frame, driving connections between said motor and said kerf cutter including a kerf cutter driving element, a horizontal transversely extending shaft driven by said driving element, mechanism driven by said shaft for swinging said kerf cutter, mechanism driven by said shaft for feeding the machine, and mechanism driven by said shaft for propelling the machine during transport. 38. In a mining machine, a frame, a kerf cutter pivotally mounted on said frame, a motor on said frame, driving connections between said motor and said kerf cutter including a kerf cutter driving element coaxial with the kerf cutter pivot, a shaft alined with and driven by said kerf cutter driving element, mechanism driven by said shaft for feeding the kerf cutter during the cutting operation, and mechanism driven by said shaft for bodily propelling the machine during transport. 39. In a mining machine, a frame, a kerf cutter pivotally mounted on said frame, a motor on said frame, driving connections between said motor and said kerf cutter including a kerf cutter driving element, a shaft coincident with the kerf cutter pivot and driven by said kerf cutter driving element, mechanism driven by said shaft for swinging said kerf cutter, and mechanism driven by said shaft for feeding the machine. 40. In a mining machine, a frame, a kerf cutter pivotally mounted on said frame, a motor on said frame, driving connections between said motor and said kerf cutter including a kerf cutter driving element, a shaft alined with and driven by said kerf cutter driving element, mechanism driven by said shaft for swinging said kerf cutter, mechanism driven by said shaft for feeding the kerf cutter, and mechanism driven by said shaft for propelling the machine during transport. 41. In a mining machine, a frame, a kerf cutter pivotally mounted thereon, a motor on said frame, driving connections between said motor and said kerf cutter including a horizontal transversely extending shaft, a kerf cutter driving element, and gearing connecting said shaft and driving element in driving relation, a parallel shaft driven by said gearing, mechanism driven by said parallel shaft for feeding the machine at a cutting speed, and mechanism driven by said parallel shaft for swinging said kerf cutter about its pivot.

MORRIS P. HOLMES.
